UNITED STATES PATENT OFFICE.

RUSSELL MOYER, OF WILLIAMSTOWN, PENNSYLVANIA.

GAS HUMIDIFIER.

1,405,062.

Specification of Letters Patent. Patented Jan. 31, 1922.

Application filed November 6, 1919. Serial No. 336,192.

To all whom it may concern:

Be it known that I, RUSSELL MOYER, a citizen of the United States, residing at Williamstown, in the county of Dauphin 5 and State of Pennsylvania, have invented certain new and useful Improvements in a Gas Humidifier, of which the following is a specification.

The invention relates to means for supplying moisture to gas in the operation of internal combustion engines. Many advantages result from the addition of moisture to the gaseous mixture of internal combustion engines, hence it is desirable to render 15 the gas moist. By supplying moisture to the gaseous mixture the power of the engine is increased by the expansion of the mixture, the cylinder is cooled, carbon prevented from depositing and a saving of fuel results.

The drawings illustrate a preferred embodiment of the invention. However, it is to be understood that I may make various changes in adapting the same to meet different conditions, without departing from 25 the nature of the invention as claimed hereinafter.

Referring to the accompanying drawings:—

Figure 1 is a sectional detail of a gas humidifier embodying the invention, and

Figure 2 is a detail view of the controlling valve.

Corresponding and like parts are referred 35 to in the following description and indicated in both views of the drawings by like reference characters.

The humidifier embodies a vaporizer 1 which is adapted to be connected with the carburetor, not shown, in any suitable way 40 so as to supply moisture thereto in the form of vapor. As indicated the vaporizer consists of two members which have a right angular arrangement. An exhaust pipe 2 extends through a portion of the vaporizer to heat the same and convert the water into vapor or steam. The exhaust pipe 2 is adapted to make connection with the exhaust manifold of the engine so as to carry 45 off the spent gases. A cup 3 is attached to the exhaust pipe 2 so as to form in effect a part thereof, and this cup is adapted to receive the moisture which is vaporized or converted into steam by the heat resulting from 50 the passage of the exhaust or spent gases

through the pipe 2. A screen 4 is associated with the cup 3 and extends across the space formed between the cup 3 and the upper wall of the vaporizer 1. The screen 4 insures the delivery of the moisture to the cup 60 and assists materially in vaporizing the water.

A valve casing 5 is connected with the vaporizer and as shown consists of a T-fitting. Other fittings 6 and 7 are coupled to the branches of the T-fitting 5. A supply pipe 8 is coupled to the fitting 6 and is adapted to be connected to the water jacket of the engine or to the upper portion of the radiator or to any source of water supply. 70 A pipe 9 is connected to the fitting 7 and is adapted to be connected to the intake manifold so that the suction stroke of the piston creates a suction therein which is utilized as means for automatically controlling 75 the valve whereby moisture is supplied to the vaporizer.

A valve 10 is mounted in the fitting 7 and is adapted to close the opposing ends of the supply and suction pipes. One end of the 80 valve 10 is made tapering as indicated at 11 and shuts off the supply by closing the end of the fitting 6 extending into the fitting 5. The opposite end of the valve 10 is provided with a disk 12 which closes the end of the 85 suction pipe 9 adjacent and coupled to the fitting 7. An expandable helical spring 13 normally exerts a pressure on the valve 10 to hold its end 11 seated against the inner end of the fitting 6 thereby normally shutting off the supply of moisture. The fittings 5 6 and 7 constitute in effect the valve casing and the parts 10, 11 and 12 constitute 90 an alternating valve, because when the valve 11 is seated, the disc 12 is unseated and vice versa.

In practice the supply pipe 8 is adapted to be coupled to a source of supply of moisture and the pipe 9 is adapted to be connected to a part whereby a suction is created therein. The supply of moisture is normally cut off by the valve 11 in the manner stated. When the engine is running and suction is created in the pipe 9, the valve 12 is drawn to its seat thereby unseating the 100 valve 11 and admitting of moisture being drawn into the vaporizer by the suction through the carburetor in a manner well understood. The moisture entering the vaporizer is received in the cup 3 and is converted 105 into steam by the heat resulting from the passage of the exhaust or spent gases. 110

ed into steam or vapor by the heat of the exhaust or spent gases passing through the pipe 2.

Having thus fully described my invention what I claim as new and desire to secure by Letters Patent, is:—

A device of the character described comprising a chamber, an exhaust pipe extending into said chamber, a cup resting upon 10 said exhaust pipe within said chamber, a porous suspension cylinder for said cup, a water supply pipe, a union connecting said

porous suspension cylinder with said water supply pipe, a valve mechanism adapted to control the entrance of water from said supply pipe to said cup, and suction means acting directly upon the valve for controlling the operation thereof.

In testimony whereof I affix my signature in presence of two witnesses.

RUSSELL MOYER.
